UNITED STATES PATENT OFFICE.

LAWSON HENRY GIDDINGS, OF PASADENA, CALIFORNIA.

ELECTRICAL OVEN AND KILN.

1,130,392.

Specification of Letters Patent.

Patented Mar. 2, 1915.

Application filed June 29, 1911, Serial No. 636,088. Renewed July 20, 1914. Serial No. 252,104.

To all whom it may concern:

Be it known that I, LAWSON HENRY GIDDINGS, a citizen of the United States, residing at Pasadena, in the county of Los Angeles and State of California, have invented a new and useful Electrical Oven and Kiln, of which the following is a specification.

This invention relates to an apparatus 10 adapted for use as a baker's oven or as a pottery, brick, malt or other kiln, or for baking or drying substances requiring such operation; and also as a tempering and annealing oven or kiln for metal working.

15 The invention may be constructed either in circular or angular plan, the circular form being preferred for strength and to guard against liability of damage from expansion and contraction.

20 The accompanying drawings illustrate the invention.

Figure 1 is a front elevation of a circular kiln constructed in accordance with this invention. Fig. 2 is a vertical section of the 25 kiln shown in Fig. 1. Fig. 3 is a view partly in section on line α^3 , Fig. 2. Fig. 4 is a plan section on line α^4 , Figs. 1 and 2. Fig. 5 is a front elevation of a rectangular kiln or oven constructed in accordance with this invention. Fig. 6 is a sectional elevation of the kiln shown in Fig. 5, from line α^5 , Figs. 7, 8 and 9. Fig. 7 is a sectional elevation from line α^6 , Fig. 6. Fig. 8 is a plan section on line α^6 , Figs. 5, 6 and 7. Fig. 9 is a plan section on line α^9 , Figs. 5, 6 and 7. Fig. 10 is a reduced sectional elevation from line α^{10} , Figs. 5, 6, 8 and 9.

The kiln or oven is provided with chambers arranged beside each other and communicating with each other at two levels and constituting the resistance chamber having an air inlet at its lower part, and the oven chamber having a draft outlet at the lower part for discharge of heated air, steam or gas. Preferably the two chambers communicate with each other at top and bottom.

Referring now to the circular form shown in Figs. 1, 2, 3 and 4, the foundation 1 supports the external heat insulating wall 2 and the refractory heat-transmitting wall 3, both of which are circular in plan section and are spaced apart to form between and within them the resistance chamber 4 and the oven chamber 5, which are beside each other so that heat from the resistance chamber 4 will

pass through the wall 3 to heat the oven chamber 5.

The heat insulating wall 2 supports the heat insulating top 6 and the heat transmitting walls 3 support the permeable oven top 7 which is spaced apart from the heat-insulating top 6 to form an air chamber 8 overlying the oven top 7 and communicating with the ports 9 in said oven top, so that the chambers 4 and 5 communicate at their tops through the air passage 8 and perforations 9. The chambers 4 and 5 communicate at their bottoms through ports 10. Ports 11 open from the external air through the heat insulating walls 2 into the resistance chamber 4. The ports 10 and 11 are arranged in alined pairs and both ports of any pair may be wholly closed or wholly opened, or the inner one may be partly or wholly opened 75 while the outer one is closed. The closures for this purpose may be any form of damper as the burnt fire-clay plugs 12 having handles 13, and adapted to be inserted into and withdrawn from said ports to control the 80 flow of air within the judgment of the operator. Bridges 14 formed by bricks projecting from either of the walls 2 or 3 extend across the resistance chamber in checker-work form to support the resistance 85 15 which may be calorite rods laid on the bridges but may be calorite, cast-iron, German silver or any other suitable resistance material capable of standing high heat. A draft outlet 16 which may be centrally arranged as shown in Figs. 2 and 4 communicates with the external air through a flue 17 extending under a portion of the floor and opening into the stack 18. The resistance rods 15 are connected in series by connectors 90 19 and with opposite poles of an electrical supply not shown through the connectors 20 and 21 and switch 22. In the form shown connection for direct current is illustrated. Alternating current of any suitable phase 100 may be used by employing suitable connections well-known in the electrical engineering art. A door-way 23 is provided and may be closed by any suitable means as by brick-work 24 shown in Fig. 1.

In the form shown in Figs. 5, 6, 7, 8 and 9, there is a heat-insulating wall 25 and a heat-conducting wall 26 on each side of the oven chamber 27, thus forming beside the chamber 27 a resistance chamber 28 corresponding to the chamber 4 of the circular form except that it is straight instead of curved. The

top 29 of the oven chamber is supported by the heat conducting wall 26 and is permeable being perforated with ports 9" arranged the same as the ports 9 of the circular form shown in Figs. 1, 2, 3, 4.

5 The rectangular form shown in Figs. 5, 6, 7, 8, 9, 10 is designed for a bake oven and the same is provided with a vertically sliding door 30 counter-balanced by the pulley 10 supported line 31 and weight 32 in a common way. In other respects than heretofore noted the construction of the rectangular oven is practically the same as that described for the circular oven, and many of the elements in Figs. 5 to 10 inclusive, that correspond to parts shown in Figs. 1, 2, 3, 4 are indicated by corresponding characters with indices.

15 The ports 9 and 9" will be located at such points as may, in the judgment of the constructor, be preferable for the particular work in view. Sometimes it may be advisable to introduce the air in greater volume on one side than the other, of the oven; 20 or near the periphery or only at the center; in each of which cases the ports will be located as desired. No illustration is attempted of all the different arrangement of ports that may be employed. The stack may 25 or may not be provided with a damper in the usual manner. No such damper is shown in the drawings as it is preferred to control the draft by means of the plugs 12 which may be pushed in so as to open the outer 30 and close the inner of its alined ports, thus admitting air to the resistance chamber 4 only; or may be drawn out by the handle 13 so as to close both ports 10 and 11; or may 35 be drawn out only sufficiently far to open 40 the inner port 10 and leave the outer port 11 closed; or may be entirely removed thus allowing both alined ports to be open.

45 In practical use the substance to be heated or baked will be placed inside the heating chamber 5 and the door way will be closed and the current turned onto the resistance. The outside ports 11 will be closed so that no external air is admitted, and the inner ports 10 will be open so that air may circulate freely from and through the chambers 50 and inner ports. The hot air will be retained in the retort by the gravity of the colder air in the flue 17 and stack 18; but any pressure from steam or gases formed, 55 and from expanded air is relieved by the opening 16, flue 17 and stack 18. The further operation of the furnace can be directed and controlled by the attendant in accordance with his judgment depending 60 upon the use for which the oven or kiln is employed.

65 The column of air in the stack and the air in the flue under the floor of the inner oven chamber serves as a yielding seal for the outlet 16 that is below the levels of the ports

which communicate between the chambers; and such seal will be maintained automatically during all the heating, oxidizing, baking and burning operations. The material known as calorite is the common general 70 electric resistance composed of nickel and chromium.

I claim:-

1. A kiln or oven comprising outer and inner chambers, ports between the chambers 75 at top and bottom thereof, an air-chamber overlying the top of the inner chamber and communicating with the top ports, electrical resistance in one of the chambers, a stack, an outlet in the floor of the other chamber, and 80 a flue connecting between the outlet and the stack.

2. A kiln or oven comprising two chambers communicating with each other at two levels, resistance in one of the chambers; 85 there being an outlet from the other chamber below both of said levels, and means to yieldingly seal the outlet.

3. A kiln or oven comprising two chambers communicating with each other at two 90 levels, electrical resistance in one of the chambers; there being inlets for external air into such chamber; means to close said inlets, there being an outlet from the other chamber below both of said levels, and 95 means to yieldingly seal said outlet.

4. A kiln or oven comprising two chambers communicating with each other at two levels, electrical resistance in one of the chambers; there being an outlet from the 100 other chamber, and alined ports in the walls of the two chambers; plugs slidale in said ports to control the same, and means to yieldingly seal the outlet.

5. A kiln or oven comprising an outer 105 wall; an inner wall; there being a chamber between said walls; bridges in said chamber; electrical resistance on the bridges; there being ports at top and bottom of the inner wall and an outlet from the inner 110 chamber below the levels of said ports; and means to yieldingly seal the outlet.

6. A kiln or oven comprising an outer wall; an inner wall; there being a chamber between said walls; bridges in staggered relation with each other in said chamber; electrical resistance on the bridges; there being ports at top and bottom of the inner wall, and an outlet from the inner 115 chamber below the levels of said ports; and means to yieldingly seal the outlet.

7. A kiln or oven comprising an outer wall; an inner wall; there being a chamber between said walls; bridges in said chamber; electrical resistance on the bridges; there being ports at top and bottom of the inner wall, and an outlet from the inner 120 chamber below the levels of said ports; a flue leading from the outlet, and a stack 125 communicating with the flue.

8. A kiln or oven comprising an outer wall; an inner wall; there being a chamber between said walls; bridges in said chamber; electrical resistance on the bridges; there being ports at top and bottom of the inner wall, and an outlet from the inner chamber below the levels of said ports; a flue leading from the outlet; a stack communicating with the flue; there being ports in the outer wall, and means to close said ports.
9. A kiln or oven comprising an outer wall; an inner wall; there being a chamber between said walls; bridges in said chamber; electrical resistance on the bridges; there being ports at top and bottom of the inner wall, and an outlet from the inner chamber below the levels of said ports; a flue leading from the outlet; a stack communicating with the flue; there being alined ports in the outer and inner walls; and plugs slidale in said ports to open and close the same.
10. A kiln or oven comprising two walls forming chambers communicating with each other at two levels, bridges formed between the walls, and electrical resistance on the bridges.
11. A kiln or oven comprising two chambers communicating with each other at two levels, and electrical resistance in one of the chambers and substantially encircling the other chamber.

In testimony whereof, I have hereunto set my hand at Los Angeles, California, this 22nd day of June, 1911.

LAWSON HENRY GIDDINGS.
